CLAIM

The ornamental design for a garment having a pocket as shown and described.

DESCRIPTION

FIG. 1 is a front elevation view of an embodiment of a garment having a pocket showing my new design; and, FIG. 2 is a front elevation view of a second embodiment of a garment having a pocket showing my new design.

The broken lines showing portions of a garment illustrate environmental structure and form no part of the claimed design. The broken lines in FIG. 1 showing the hood, neck, and sleeve on the garment depict environmental structure and form no part of the claimed design. The broken lines in FIG. 2 showing the neck and sleeve on the garment depict environmental structure and form no part of the claimed design.

1 Claim, 2 Drawing Sheets(56)
